[57] **CLAIM**

The ornamental design for a blanket hold-down clip, as shown.

DESCRIPTION

FIG. 1 is a front, top, side perspective view of the blanket hold-down clip showing my new design;

FIG. 2 is a top plan view thereof;

FIG. 3 is a side elevational view taken from the left of FIG. 1;

FIG. 4 is a front elevational view thereof;

FIG. 5 is a side elevational view taken from the right of FIG. 1;

FIG. 6 is a rear elevational view thereof;

FIG. 7 is a bottom plan view thereof.
